Filed Nov. 25, 1964, Ser. No. 82,782

Term of patent 14 years

(Cl. D10—7)

FIG. 2.

FIG. 3.

FIG. 1.

FIG. 4.

FIG. 1 is an elevational view of a door knocker, showing my new design;

FIG. 2 is a plan view thereof;

FIG. 3 is a left side elevation thereof; and

FIG. 4 is a sectional elevation taken along line 4—4 of FIG. 1.

The right side not shown is similar to the left side and the back is plain. The dominant features of the design reside in the portion shown in full lines.

I claim:

The ornamental design for a door knocker, as shown and described.
